ARTIFICIAL BAIT

Kenneth H. Reed, Saginaw, Mich.

Application May 20, 1947, Serial No. 749,148

3 Claims. (Cl. 43—35)

1

This invention relates to an artificial bait, and more particularly to such a bait of the plug type.

A primary object of this invention is the provision of an improved artificial bait which may be readily cast or trolled, characterized by a plurality of normally retracted hooks adapted to be extended upon the application of pressure to a trigger, as by a striking fish, the normal retraction of the hooks precluding the catching of the device in weeds or the like.

An additional object of the invention is the provision of such a device provided with a rotatable head, adapted to attract and lure fish by imparting a relatively lifelike motion to the device.

A further object of the invention is the provision of such a device having a weighted end cap, whereby when cast, the device will strike the water nose first in such manner as to preclude the accidental tripping of the trigger.

A still further object of the invention is the provision of such a device which may be readily and expeditiously set with a minimum effort and difficulty.

Still other objects will in part be obvious and in part be pointed out as the description of the invention proceeds, and shown in the accompanying drawings, wherein there is disclosed a preferred embodiment of this inventive concept.

In the drawings:

Figure 1 is a top elevational view of a device embodying features of the instant invention, certain concealed portions thereof being indicated in dotted lines.

Figure 2 is a sectional view taken substantially along the center line of Figure 1, certain parts thereof being disclosed in alternative positions of adjustment by dotted lines.

Figure 3 is a sectional view taken substantially along the line 3—3 of Figure 2, as viewed in the direction indicated by the arrows, on an enlarged scale.

Figure 4 is an enlarged sectional view taken substantially along the line 4—4 of Figure 2, as viewed in the direction indicated by the arrows.

Figure 5 is an end elevational view of the device shown in Figure 1, as viewed from the rear or right hand side thereof.

Figure 6 is a transverse section, taken on the line 6—6 of Figure 2 adjacent the rear end of the sliding tube and looking toward the end of the base.

Similar reference characters refer to similar

2

parts throughout the several views of the drawings.

Referring now to the drawings in detail, the device of the instant invention is comprised of a main body portion 10 of symmetrical shape, provided with an interior bore 11, within which is positioned a tube 12 extending forwardly of the end 13 of body portion 10. Forwardly of the tube 12 there is provided an extension 14, which engages at the front end the bearing ring 15, and at its extremity there is secured a threaded projection 16, engaging the nut 17. A supplemental body portion 18 is mounted on the extending portion of tube 12 and the tube 14, and is adapted for rotation against bearing ring 15 and a bearing collar 19 which surrounds a reduced portion of the body 10, and is provided with a flange 20 forming a thrust bearing for the end of member 18. As best shown in Figure 1, the member 18 is provided with a plurality of helical grooves 21, the arrangement being such that as the device is drawn forwardly through the water, and the impact of the water in the grooves 21 will serve to rotate the member 18.

25 A weighted end cap 22 provided with an interior threaded bore is adapted to threadedly engage the projecting portion 16 under circumstances to be more fully described hereinafter. The end cap 22 is provided at its extremity with a ring 23, to 30 which may be attached a leader 24, or line, as may be desired. Secured interiorly of the end cap 22 is a rod 25 which extends interiorly of the tubes 14 and 12, and is provided at its intermediate point with a collar 26 slidable thereon and abutting an end of the slidable tube 30. One end of a compression spring 27 is adapted to seat against the collar, the other end thereof being positioned against the extremity of the tube 14. Rearwardly of the collar 26, the rod 25 extends 35 interiorly of a tube 30, which tube has fixed to its extremity a plate 31. The plate 31 is seated in an enlarged recessed aperture at the rear of the device, the aperture being provided at diametrically opposed points with slots 32, through which are adapted to be extended hooks 33, the hooks lying in the position disclosed in full lines in Figure 2 completely interiorly of the body portion in the slots when in retracted position. Each hook is pivotally connected, as by a pivot ring 34, to the body portion, and includes a loop 35 which forms pivotal connection with a link 36, the opposite end of which is secured in a suitable aperture in the plate 31. In the preferred embodiment of this invention there are four hooks, each

adapted to be extended outwardly through an appropriate slot.

From the arrangement thus described, it will be seen that when the plate 31 is in the position disclosed in full lines, the pivotal arrangement is such as to withdraw the hooks. Conversely, when the plate is extended to the dotted line position shown in Figure 2, the hooks will be extended.

Means are provided for holding the plate 31 in retracted position, and consequently the hooks 33, as well as to release the same when desired, and take the form of a trigger bar 40 adapted to extend through the top slot 32, which is enlarged to accommodate the same. The trigger member or bar 40 comprises a bifurcated member, as best shown in Figures 1 and 3, between the bifurcations of which extends one of the hooks 33. The rear extremity of the trigger bar 40 extends outwardly through a slot 41 in an end plate 42 adapted to close the rear of the recess in the rear of the body portion, as best shown in Figure 5, the extending portion being adapted to be struck and dislodged by a fish in a manner to be more fully described hereinafter. Trigger bar 40 includes an abutment 44 adapted to bear against the edge of the plate 31 when the latter is in retracted position, and is pivoted at its extremity to a pivot point 45 fixed on the rear end of the spring plate 47. A pin or tongue 46 extends downwardly from the pivot point 45, and is adapted to pass through an aperture in a leaf spring 47 on which the pivot 45 is secured, and then into an aperture 48 in a ramp portion 49 secured to the tube 30. Obviously, with the trigger bar shown in the position in full lines in Figure 2, engagement of pin 46 in aperture 48 will preclude movement of the tube 30 and its associated plate 31, and consequently extension of the hooks 33.

However, upon moving of the trigger bar 40 to the dotted line position shown in Figure 2, such as might be occasioned by the striking of a fish, it will be understood that the pin 46 will be released from its associated aperture 48, whereupon the spring 27 will serve to move tube 30 and its associated plate 31 to the dotted line position, thus extending the hooks 33, which will embed themselves firmly in the mouth of a fish.

When it is desired to re-set the device, it will be understood that the rod or cocking member 25, which extends completely through the tube 30 and a suitable aperture in plate 31 and terminates in a collar or washer 50, may, by unthreading the nose portion 22 from threaded extremity 16, be drawn outwardly, which will retract the plate 31 until the spring 47 biases pin 46 into aperture 48, retaining the hooks in retracted position. Since the rod is normally freely slidable in the tubes 14 and 30, the nose cap may be replaced and re-threaded into position after setting, whereupon the device is ready for re-use.

If desired, a suitable weight 51 may be positioned in the base of the device in such manner as to hold the trigger bar 40 in upright position, as shown in Figure 2, so that when the device is cast, it will land nose down or bottom portion down, in order to preclude dislodgment of the trigger bar and its associated mechanism upon impact with the water.

From the foregoing it will now be seen that there is herein provided an improved artificial bait, which accomplishes all the objects of this

invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

10 I claim:

15 1. In an artificial bait comprising a body having a longitudinally extending bore therein, a plurality of hooks pivoted onto the body for extension from and retraction therein, a member 20 slidable in said body and operatively connected to said hooks, an apertured ramp portion secured to said member, a plate secured to the rear end of said member, a collar abutting the front end of said member, spring means in said body 25 engaging said collar for pivoting said hooks to extended position, a spring pressed pin engaging the aperture in said ramp portion for latching said member in hook retracting position, a trigger bar engaging said pin and rockable on said plate for releasing said pin from engagement with said apertured ramp portion, and a cocking member in said body engaging said slidable member for resetting said slidable member and re-tracting said hooks.

30 2. In an artificial fish lure comprising a body, hooks pivoted on said lure for retraction therein and extension therefrom, a member slidable in said body and operatively connected to said hooks, an apertured ramp portion secured to said member, a collar abutting said member, resilient means pressing said collar to hook extending position, a spring pressed member in said body engaging said apertured ramp portion for holding said slidable member in hook retracting position, and a trigger bar extending from said body and engaging said spring pressed member for releasing said spring pressed member to hook extending position.

35 3. In an artificial fish lure, hooks pivoted on said lure for retraction therein and extension therefrom, a member slidable in said lure and operatively connected to said hooks, an apertured ramp portion secured to said member, a plate secured to the rear end of said member, a collar abutting the front end of said member, resilient means pressing said collar to hook extending position, a spring pressed pin in said lure engaging the aperture in said ramp portion for holding said slidable member in hook retracting position, and a trigger bar extending from said lure and engaging said pin for releasing said slidable member to hook extending position, and a cocking member in said lure engaging said slidable member for retracting said member to hook re-extending position.
